UNITED STATES PATENT OFFICE.

EMANUEL W. SWEIGARD, OF CHICAGO, ILLINOIS.

PRINTING-FRAME.

No. 835,205.

Specification of Letters Patent.

Patented Nov. 6, 1906.

Application filed April 19, 1906. Serial No. 312,533.

To all whom it may concern:

Be it known that I, EMANUEL W. SWEIGARD, a citizen of the United States of America, residing at Chicago, in the county of Cook and State of Illinois, have invented certain new and useful Improvements in Printing-Frames, of which the following is a specification.

My invention relates to improvements in printing-frames, and is fully described and explained in this specification and shown in the accompanying drawings, in which—

Figure 1 is a side elevation of my improved device. Fig. 2 is a vertical section in the line 2 2 of Fig. 3. Fig. 3 is a front elevation of one of the bar-clamping devices, and Fig. 4 is an elevation of that portion of the clamping device which is secured to the printing-frame proper.

The frame herein illustrated is intended as an improvement in certain particulars upon that shown and described in my patent granted May 10, 1898, No. 603,713, and it will be observed that for the most part my device shows the general construction shown in said patent. Thus A is a hollow rectangular frame adapted to receive a plate of glass B, upon which a negative C is laid with its film side up, and upon this negative C is laid the print D, which may be either a sheet of sensitized paper, or, more often, a sheet of zinc, such as is used in photo-engraving and like processes. Upon this "print," as I shall call it for convenience, is placed a pressure-board E, upon the back of which are placed a number of elastic struts or cushions F, of rubber or other desired material, which may be arranged as shown in my prior patent or in other ways, as desired. Along the rear of the frame are secured a plurality of hinges g, which support a plurality of swinging bars G, which when pressed down at their forward ends will clamp the pressure-board against the plate, thus producing the proper contact between the print and the negative. Along the front of the frame A are secured a plurality of brackets H, provided with furcations h, adapted to receive between them the upwardly-projecting ends of bifurcated members I, mounted upon the forward ends of the bars G. The furcations of the brackets operate to receive said members, and thereby to center and position the forward ends of the bars G, which, owing to the imperfections in the hinge construction at the rear thereof, have necessarily some lost motion in a hori-

zontal plane. The members I support between their furcations levers J, each of which is provided with an elongated handle j and a recurved hook portion j'. The brackets H support loops K, capable of swinging backward and forward, the backward movement being limited by contact with the frame A and the forward movement being limited by shoulders h' on the bracket H. It will be seen that these loops when in their forward position (shown in Fig. 2) strike the handle j of the lever J and that by rotating said levers the loops will be caused to pass between the handle and the hooked portion of said lever, so that when the levers are turned back over the frame, as shown in Fig. 1, the loops will have moved to the position shown therein, so as to produce a toggle-clamping action on the pressure-board.

The lever J is provided with a hump J', just behind that portion of the lever which is first struck by the loop as the pressure-bar is swung downward. If this hump were omitted and the lever were straight from the point where the loop is shown in contact therewith, Fig. 2, up to the base of the hooked portion, assuming that the lever and loop would slide on each other with a fair degree of ease and that there was no undue binding between the loop and bracket, the contact of the lever with the loop would merely cause the loop to slide up along the lever, a wedging action taking place to effect this result. The loop would slide up to the very base of the hook portion and would then be in no position to exert any rotating tendency upon the lever, with the result that the levers would have to be positively closed by hand. This is substantially true of the device of my prior patent. When the loops strike the levers upon the forcible throwing down of the bars, the loops tend merely to slide up the levers until they reach substantially the dead-center and then exert no rotating force thereon. If, however, the friction between the loops and brackets is higher than normal, this inward movement of the loops will be prevented, and the throwing down of the bars will cause the lever to swing around so as to clamp the bars automatically, and this is the operation set out in the patent. This action only takes place, however, in the device of the patent when the friction between the brackets and loops is considerable, and it tends to disappear, therefore, as the device becomes worn.

My present invention is designed primarily to produce a structure which will lock itself automatically under all conditions, and this result is produced by placing the hump 5 *J'* upon the lever. By this means the surface of the lever against which the loop strikes is almost at right angles to the loop, and there is consequently little or no tendency for the loop to slide upward along the lever instead of rotating it. As a result, with my present device, regardless of the amount of friction and the force with which the cross-bar is thrown down, the loop remains in its forward position and causes 15 rotation of the lever about its pivot until it almost reaches the dead-center, and backward movement of the loop is never caused by its sliding up along the bottom face of the lever with a wedge-like action, but rather by 20 engagement with the surface of the recurved hook portion *j'* thereof. In other words; my present device is so arranged that the angle between the surface of the lever with which the loop first contacts and those portions of the surface with which it remains in 25 contact as the lever rotates is such that there is no wedging force exerted which can move the loop backward. In fact, this angle is substantially a right angle, so that there is 30 never any wedging tendency, or, if any such tendency should exist, it is one which tends to throw the loop forward instead of backward.

I realize that considerable variation is possible in the details of this construction without departing from the spirit of my invention, and I do not intend, therefore, to limit myself to the specific form herein shown and described except as required by the scope of 40 the appended claims.

I claim as new and desire to secure by Letters Patent—

1. The combination with a frame, of a hinged cross-bar, a loop pivoted to the frame 45 adjacent to the forward end of the cross-bar,

means for limiting the forward swing of the loop, and a hooked lever pivoted to the cross-bar and adapted to engage the loop, the portion of the lever which contacts with the loop when the bars are swung down being 50 so arranged as to resist the inward movement of the loop along the lever.

2. The combination with a frame, of a hinged cross-bar, a loop pivoted to the frame adjacent to the forward end of the cross-bar, 55 means for limiting the forward swing of the loop, and a hooked lever pivoted to the cross-bar and adapted to engage the loop, the portion of the lever which contacts with the loop being so arranged as to present a surface substantially at right angles to the loop on the initial contact of the lever and loop. 60

3. The combination with a frame, of a hinged cross-bar, a loop pivoted to the frame adjacent to the forward end of the cross-bar, 65 means for limiting the forward swing of the loop, and a hooked lever pivoted to the cross-bar and adapted to engage the loop, the portion of the lever which contacts with the loop being so arranged as to cause no inward 70 wedging of the loop.

4. The combination with a frame, of a hinged cross-bar, a loop pivoted to the frame adjacent to the forward end of the cross-bar, 75 means for limiting the forward swing of the loop, and a lever provided with a recurved hook adapted to engage the loop pivoted upon the cross-bar, said lever being provided with a hump within the hook, and in position to strike the loop when in its forward position and to prevent the said wedging of the hook with the rotation of the lever. 80

In witness whereof I have signed the above application for Letters Patent, at Chicago, in the county of Cook and State of Illinois, 85 this 17th day of April, A. D. 1906.

EMANUEL W. SWEIGARD.
